UNITED STATES PATENT OFFICE

MAJOR DUNCAN, OF BALTIMORE, MARYLAND

VENDING MACHINE

Application filed August 7, 1928. Serial No. 298,118.

My invention relates to vending machines and more particularly to machines for vending flat articles such as newspapers, periodicals, etc.

5 An object of the invention is to provide a coin controlled mechanism having a slideable drawer for singly delivering the articles which is only permitted to be withdrawn to deliver articles after a requisite number of 10 coins have been deposited into the machine.

Further the invention provides a normally latched coin controlled drawer which is permitted to be withdrawn step by step to full delivery position upon singly depositing 15 a number of coins into the machine.

With the preceding and other objects and advantages in mind, the invention consists in the novel combination of elements, constructions and arrangement of parts to be 20 hereinafter specifically referred to, claimed and illustrated in the accompanying drawings, wherein:

Figure 1 is a perspective of the machine,
Figure 2 is a horizontal sectional view of 25 the same taken on line 2—2 of Figure 1,

Figure 3 is a vertical transverse sectional view,

Figure 4 is a fragmentary perspective having parts shown in section and parts in 30 elevation,

Figure 5 is a transverse sectional view taken on line 5—5 of Figure 2,

Figure 6 is a similar view showing the 35 drawer in partially withdrawn position,

Figure 7 is an enlarged fragmentary vertical section view taken on line 7—7 of Figure 1.

Figure 8 is a perspective of one of the elements embodied in the invention,

Figure 9 is a longitudinal sectional view taken on line 9—9 of Figure 2,

Figure 10 is a transverse vertical section taken on line 10—10 of Figure 3,

Figure 11 is a perspective of the machine with the drawer thereof in withdrawn position,

Figure 12 is a rear end elevation, and

Figure 13 is a longitudinal sectional view taken on line 13—13 of Figure 2.

50 Referring to the invention in detail a

rectangular cabinet 5 having a hinged lid 6 is provided and is adapted to be mounted on a vertical post 8 by means of brackets 9 secured to the rear wall thereof, and which are secured to the post by a conventional 55 lock 10.

In order to singly deliver newspapers or other analogous articles placed in the cabinet, a channel shaped drawer 11 is slidably mounted upon the bottom wall of the cabinet 60 and is adapted to be withdrawn therefrom through a slot 12 extending the entire length of the front wall of the cabinet. As particularly illustrated in Figure 10, one of the side flanges of the drawer is slideable in 65 an inverted L-shaped guide 13 mounted upon the bottom wall of the cabinet at one side thereof. To limit the withdrawal of the drawer a pair of parallel rods 14 are secured to the lower ends of plates 15 attached to the front wall of the drawer and projecting below the same. These rods 14 are longitudinally movable in a rectangular chamber 16 provided on the under face of the bottom of the cabinet and extending the 70 entire length thereof. Attached to these rods is a cross head 17 which contacts with the front wall of the cabinet when the drawer is in full withdrawn position. In addition to the cross head limiting the outward movement of the drawer, it serves to guide the drawer in a true horizontal direction so that it will readily pass through the slot 12. 75

For the purpose of separating the lowermost article contained in the cabinet, a 80 normally horizontally disposed plate 18 is hinged to the upper face of the drawer at one end thereof as indicated at 19. This plate is maintained in spaced relation to the drawer by means of a down-turned flange 85 20 formed on the free end of the plate and angle brackets 21 formed on the forward longitudinal edge thereof. The rear longitudinal edge of the plate is bevelled as at 22 to facilitate passing of the plate between the 90 bottom article and the one next in order so that the bottom article will lie upon the drawer each time it is moved into the cabinet. 95

As illustrated in Fig. 11 the plate is 100

formed with a rearwardly extending extension 15^a provided with a hinge pin 16^a which is received in a slotted bracket 17^a secured to the drawer 11. To compensate for newspapers of various thicknesses, adjusting screws 18^a pass through the opposite ends of the plate 18 and are adjustable against the drawer 11 to regulate the height of this plate.

10 A coin controlled mechanism is provided for controlling the withdrawal of the drawer. This mechanism comprises a channel shaped member 23 extending along one of the end walls of the cabinet and adjacent edge of the drawer. As illustrated in Figure 8, the channel shaped member is formed with a coin receiving opening 24 in one face and an angularly disposed lip or guide 25 below the same. As illustrated in Figure 7, the coin opening 24 registers with an inclined slot 26 in the adjacent side wall of the cabinet which merges into a circular coin entrance opening 27 at its upper end. A coin ejector 28 is movable longitudinally in the channel shaped member and is normally urged towards the forward end thereof by means of a flexible element 29 trained over pulleys 30 and connected to a contractile spring 31, the latter being secured to the rear wall of the cabinet at its upper end. A shank 32 projects laterally from the coin ejector and is movable in a longitudinal slot 33 formed in one side of the channel shaped member and communicating with the opening 24. The slot 33 is in registration with a longitudinal slot 34 formed in the adjacent end wall of the cabinet through which the shank passes. A handle 35 is carried by the outer end of the shank whereby the ejector is slid rearwardly in the channel shaped member. As particularly illustrated in Figure 4, the channel shaped member is provided with notches 36 which are successively engaged by the lateral end 37 of a pivoted latch 38 carried by the drawer adjacent its rear end. This latch is normally retained in a position to engage one of the notches by means of an expansible spring 39 interposed between the drawer and rear end of the latch. To facilitate movement of the lateral end 37 out of the notches, one of the side walls of each is bevelled, as at 40.

Arranged above the channel shaped member is a horizontal bar 41 having pairs of oppositely bevelled recesses 42 in its under face. The bar 41 is supported from a vertical cleat 43 attached to one of the side walls of the cabinet and a horizontally disposed cleat 44 secured to the bottom wall of the cabinet behind the drawer. An upstanding finger 45 is pivotally supported on a horizontal pivot pin 46 passing transversely through a rectangular casing 47. This casing 47 is attached to the drawer directly

below the bar 41 so that the finger 45 normally projects into an opening 48 provided in the bar adjacent its rear end. The finger 45 is normally retained in an angular position by coil springs 49 bearing against the finger at opposite sides and anchored in a block 49 held within the casing below the pivot pin 46. It will be observed that as the drawer is withdrawn the finger rides on the under face of the bar and successively engages one notch of each pair, thus making it impossible to partially withdraw the drawer and then push it to normal position. Reversely, the finger successively engages the other notch of each pair when the drawer is being returned to normal position. It will therefore be seen that it is necessary to complete the movement of the drawer when it is started in either direction.

15 A coin box 50 is provided rearwardly of the compartment 16 and has communication with the channel shaped member 23 by way of an opening 51 formed in the bottom of the cabinet.

20 In order to observe the contents of the cabinet, a glass or window 52 is arranged in the front wall of the cabinet.

25 In the operation of the invention the purchaser first places a coin in the opening 24 which passes into the channel shaped member through the coin recess 24. The ejector is now shoved forwardly by manipulation of the handle 35. As the ejector is moved forwardly it advances the coin to the position illustrated in Figure 5 and as the coin continues rearwardly it contacts with the lateral extension 37 lifting the latch element out of the rearmost notch 36. With the latch element thus lifted by the coin the drawer can now be partially withdrawn. In this connection it will be observed that the extension 37 of the latch element rides on the upper edge of the channel shaped member until it reaches the next notch 36. At this time the extension moves into this notch to prevent the further outward movement of the drawer. A second coin is now deposited and the ejector again actuated as above stated to disengage the latch element and permit the drawer to be fully withdrawn. When the drawer has been withdrawn the plate 18 is swung upwardly as illustrated in Figure 11 to permit the paper or other article to be removed.

30 What is claimed is:—

35 1. In combination a horizontally arranged channel shaped member into which coins are adapted to be deposited and having a notch therein, a slide movable longitudinally along the channel shaped member, a latch element carried thereby and normally engaged with the notch, and a coin pushing element slidably mounted in the channel shaped member for moving a coin into engagement with the

latch element to move the latter out of the notch.

2. In combination a channel shaped member having a plurality of spaced notches therein, a slide movable along the channel shaped member, a latch element carried thereby and successively engageable with the notches, and means for moving coins into engagement with the latch element to successively disengage the latter from the notches and permit the slide to be moved in a longitudinal direction step by step.

3. In a coin controlled mechanism, a horizontally arranged coin guide into which coins are singly deposited, a slide movable longitudinally along the coin guide, a latch element carried thereby and adapted to successively engage notches in the coin guide, and a longitudinally movable element in the coin guide for moving a coin into engagement with the latch element to render the latter inoperative and permit the slide to be moved a predetermined distance.

4. In a coin controlled mechanism, a horizontally arranged coin guide into which coins are singly deposited, a slide movable longitudinally along the coin guide, a latch element carried thereby and adapted to successively engage notches in the coin guide, a longitudinally movable element in the coin guide for moving a coin into engagement with the latch element to render the latter inoperative and permit the slide to be moved a predetermined distance, and a handle projecting from the longitudinally movable element.

5. In a coin controlled mechanism, a horizontally arranged coin guide into which coins are singly deposited, a slide movable longitudinally along the coin guide, a latch element carried thereby and adapted to successively engage notches in the coin guide, a longitudinally movable element in the coin guide for moving a coin into engagement with the latch element to render the latter inoperative and permit the slide to be moved a predetermined distance, and resilient means normally urging the longitudinally movable element in a forward direction.

6. In a vending machine, a cabinet having a coin entrance slot in one of its vertical walls, a horizontally arranged coin guide extending along such wall and having communication with the coin receiving slot and also having a plurality of spaced openings therein, a slide movable along the coin guide, a latch element pivoted thereto and successively engageable with the openings to permit predetermined movement of the slide, and means for successively engaging a coin with the latch element to render the same inoperative and permit movement of the slide.

MAJOR DUNCAN.
